UNITED STATES PATENT OFFICE

2,460,599

ELECTRIC SWITCH ACTUATOR

Raymond N. Rowe, Plainville, Conn., assignor to
 The Trumbull Electric Manufacturing Company,
 Plainville, Conn., a corporation of Connecticut

Application October 3, 1945, Serial No. 619,999

12 Claims. (Cl. 74—565)

1

My invention relates particularly to hand actuated means for controlling a two-position switch, such for instance as a switch designed to connect a work circuit to either one of two sources of current. It is the main object of my invention to compel hesitation of the mechanism in the "off" position in passing from one source to the other.

The invention is applicable to any two-position switch actuated by a rotatable shaft having a handle lever.

Fig. 1 is a front view of a fragment of the cover of an enclosed switch with actuating means embodying the preferred form of my invention, the handle being in the "off" position and ready to be thrown into position to connect with one source of current.

Fig. 2 is a vertical projection of the same showing the handle in full lines in its normal inactive "off" position and in dot and dash lines in the position for throwing the switch into connection with the alternative source of current.

Fig. 3 is a side view looking from the left of Fig. 2.

Fig. 4 is a side view looking from the right of Fig. 2.

The actuating shaft 7 of the switch mechanism (not shown) is mounted in a support 8 which would appropriately be the cover of a switch box. A cylindrical abutment member 9 surrounds this shaft and has two walls 10 and 11. The handle 12 has flanges 13 hinged on the transverse pivot 14 in the shaft 7. A spring 15 seated in the upper end of the shaft 7 presses the handle to the position of Fig. 2 where the extension 16 rests upon the lower wall 10 of the abutment member.

The two walls 10 and 11 constitute tracks extending along side of the handle in its "off" position for supporting and guiding the handle in its movement from the "off" position to the two "on" positions and the higher track 11 has abutments 17 and 18 at its opposite ends.

To connect the switch with the preferred source of current, it is merely necessary to swing the switch handle 12 from the "off" position of Fig. 1 to the upper position marked "on" during which movement the handle slides over the top of wall 11.

To connect the switch with the other source of current the handle is depressed to the dot and

2

dash position of Fig. 2 in order to raise the extension 16 over the edge of wall 11.

The end 17 of wall 11 serves as a stop to prevent clockwise swinging of the handle while in the full line raised position of Figs. 2 and 3. The end 18 of wall 11 serves as a stop to prevent anti-clockwise swinging of the handle while depressed in the dot and dash depressed position of Fig. 2.

From the foregoing, it will be seen that when the handle is swung from the upper "on" position it will be stopped by the engagement of the extension 16 against the stop 17. In order to continue the movement to the lower "on" position the handle must be depressed in order that the extension 16 can clear the top of wall 17.

In order to swing the handle from the lower "on" position to the upper "on" position, it must be stopped against the end 18 of the upper wall and then raised. Overhanging projections 19 and 20 serve to retard the movement of the handle from the "off" position toward the respective "on" positions.

The abutment wall and the handle extension may be provided with openings 21, 22, 23 in order to facilitate the attachment of locking means.

To limit the movement of the handle when turning to the "on" position I may provide the handle with a depending end 24 which may engage the abutment 25 when turning the handle 30 anti-clockwise to the upper "on" position and may engage the abutment 26 when turning the handle clockwise to the lower "on" position.

I claim:

1. In a two-position electric switch, a rotatable actuating shaft, a handle hinged to said shaft permitting said handle to be tilted, said handle having an extension beyond said shaft, stops standing in the path of movement of said handle and said extension respectively and a spring tilting said handle so that it can be rotated in one direction, the handle being rotatable in the other direction only when the spring is compressed, said stops having overhanging lips for interrupting the movement of said handle and said extension.

2. In a two-position electric switch, a rotatable actuating shaft, a handle hinged to said shaft permitting said handle to be tilted, said handle having an extension beyond said shaft, stops standing in the path of movement of said handle

and said extension respectively, a spring for tilting said handle and a supporting wall so that the handle can be rotated in one direction, the handle being rotatable in the other direction when the spring is compressed.

3. In a two-position switch, a rotatable actuating shaft, an abutment wall on each side of the "off" position of the shaft, one wall being higher than the other, a handle hinged to said shaft and having an extension, a spring normally pressing said handle so that its extension rests upon the lower wall when the handle is in the "off" position at which time the handle is free to be rotated over the higher wall to one "on" position but cannot be rotated to the other "on" position until the handle is depressed so as to raise the extension above the line of the higher wall.

4. In a two-position switch, a rotatable actuating shaft, an abutment wall on each side of the "off" position of the shaft, one wall being higher than the other, a handle hinged to a transverse pin in said shaft and having an extension, a spring normally pressing said handle so that when the handle is in the "off" position it is free to be rotated over the higher wall to one "on" position and a stop to prevent rotation to the other "on" position until the handle is depressed so as to raise the extension above the line of the higher wall.

5. In a switch having two "on" positions and an intermediate "off" position, a rotatable main shaft, a handle lever hinged to said shaft and having one end extending beyond the shaft, a supporting wall extending around each side of the central "off" position of the handle lever, one wall being higher than the other wall and serving as a track to support said handle lever as it is actuated to rotate said shaft and each end of said higher wall acting as a stop to limit the rotating of the shaft and handle lever when actuating the switch from an "on" to the "off" position.

6. In a switch having two "on" positions and an intermediate "off" position, a rotatable main shaft, a handle lever hinged to said shaft and having one end extending beyond the shaft, a supporting wall extending around each side of the central "off" position of the handle lever, one wall being higher than the other wall and serving as a track to support said handle lever as it is actuated to rotate said shaft and each end of said higher wall acting as a stop to limit the rotating of the shaft and handle lever when actuating the switch from an "on" to the "off" position and a spring normally pressing said handle lever against one of said walls.

7. In an electric switch having two alternative "on" positions and an "off" position between the "on" positions, an actuating shaft, a handle lever hinged to tilt on said shaft, two walls on opposite sides of said shaft one of which is higher than the other and has abutment shoulders coaxing with portions of the handle lever on opposite sides of the shaft, a spring normally tilting said handle lever against the lower wall, the higher wall preventing the tilting of the handle lever in all positions of the switch except the "off" position and said abutments stopping the rotation of the handle lever in moving from one "on" position to the other "on" position.

8. An electric switch control comprising, a shaft, a cylindrical support surrounding the end of the shaft and having two arcuate walls, one of which is higher than the other and has abutments at its opposite ends to limit rotation of

the handle lever, a handle lever hinged to the shaft and adapted to tilt in a plane including the axis of the shaft, a spring normally pressing the handle lever against the lower wall adjacent

5 one of the abutments when said lever is in the open circuit position so as to prevent rotation of the handle lever in one direction and permit rotation of the handle member in the other direction when the handle lever is tilted sufficiently to clear the abutment, the higher wall preventing the tilting of the handle lever while the circuit is closed, the other abutment preventing rotation of the handle lever in one direction when the handle lever is depressed.

15 9. An electric switch control comprising, a shaft, a cylindrical support surrounding the end of the shaft and having two arcuate walls, one of which is higher than the other and has abutments at its opposite ends to limit rotation of the

20 handle lever, a handle lever hinged to the shaft and adapted to tilt on an axis at right angles to the axis of the shaft, a spring normally pressing the handle lever against the lower wall adjacent one of the abutments so as to prevent rotation

25 of the handle lever in one direction and permit rotation of the handle member in the other direction when the handle lever is tilted sufficiently to clear the abutment, the higher wall preventing the tilting of the handle lever while

30 the circuit is closed, the other abutment preventing rotation of the handle lever in one direction when the handle lever is depressed, said cylindrical support having stop shoulders and said handle lever having a projection coaxing there-

35 with to limit the turning of the handle.

10. In an electric switch having two "on" positions and an intermediate "off" position a rotatable switch shaft, a handle lever hinged to the shaft and tiltable freely on an axis at right angles to the axis of the shaft and having an extension beyond the shaft and a wall constituting a continuous track extending along one side of the handle when in its "off" position for supporting the handle or its extension when the

40 shaft is rotated to either of the "on" positions, said wall having a raised portion for stopping the handle in turning from one "on" position to the other "on" position.

11. In an electric switch having two "on" positions and an intermediate "off" position a rotatable switch shaft, a handle lever hinged to the shaft and tiltable freely on an axis at right angles to the axis of the shaft and having an extension beyond the shaft and a wall constituting a continuous track extending along one side of the handle when in its "off" position for supporting the handle or its extension when the

50 shaft is rotated to either of the "on" positions, said wall having a raised portion at each end for stopping the handle in turning from one "on" position to the other "on" position, each end of

60 said wall having a lip overhanging the adjacent abutment compelling the handle lever on striking said raised portion to be turned backwardly after turning the handle lever to the "off" position from one "on" position and striking the abutment before it can be tilted and continued in movement to the other "on" position.

12. In a switch having two "on" positions and an intermediate "off" position, a cylindrical supporting member, a rotatable main shaft extending axially through the center thereof, a circular wall on said cylindrical supporting member and concentric with said shaft, one arcuate segment of said wall being raised above the remaining

portion, a crank-type handle lever hinged to said shaft on an axis perpendicular to the axis of the shaft, and having an extension beyond the shaft, said circular wall serving as a track to support said handle lever extension as said lever is actuated to rotate said shaft, each end of said raised arcuate segment of said circular wall acting as a stop to prevent overtravel of said handle lever when actuated from either "on" position to the intermediate "off" position, a spring pressing said handle lever extension against said circular wall, and abutments extending radially from said cylindrical supporting member and adapted to be engaged by a part of said handle lever extension.
